UNITED STATES PATENT OFFICE

163,300

BOOT

George Lewis, Los Angeles, Calif., assignor to
Lucky Plastics Co., Inc., Los Angeles, Calif., a
corporation of California

Application July 10, 1950, Serial No. 11,048

Term of patent 14 years

(Cl. D7—4)

To all whom it may concern:

Be it known that I, George Lewis, a citizen of the United States, residing in the city of Los Angles, county of Los Angles, and State of California, have invented a new, original, and ornamental Design for Boot, of which the following is a specification, reference being had to the accompanying drawing, forming part thereof.

On the drawing,

Fig. 1 is a side elevational view of a boot, embodying my new design;

Fig. 2 is an end elevational view of the boot shown in Fig. 1;

Fig. 3 is a plan view of the boot shown in Fig. 1;

Fig. 4 is a bottom plan view of the boot shown in Fig. 1; and

Fig. 5 is a detail sectional view of a portion of

the sole of the boot taken on the line 5—5 of Fig. 4.

As shown in Figs. 3, 4 and 5, the ribs in the sole are visible through the sole, which is of translucent material.

I claim:

The ornamental design for a boot, as shown and described.

GEORGE LEWIS.
